PUMP

Seymour J. Baum, Flushing, N. Y.

Application December 27, 1938, Serial No. 247,867

2 Claims. (Cl. 230—40)

This invention relates to pumps; and more particularly, to hand pumps for use in connection with aircraft and adaptable to a variety of purposes such as inflating or deflating pneumatic devices, forcing air through conduits or lifting water, as circumstances require.

The object of the invention is to provide an improved hand pump embodying novel means and simplified structure for obtaining the objectives indicated.

The invention consists in the novel construction, arrangement, and combinations of parts hereinafter more particularly described and claimed.

15 One sheet of drawings accompanies this specification as part hereof in which like reference characters indicate like parts throughout.

In the drawing:

Figure 1 is a vertical cross section;
20 Figure 2 is a horizontal cross section taken on line 2—2 of Figure 1;

Figure 3 is a horizontal cross section taken on line 3—3 of Figure 1; and

25 Figure 4 is a fragmentary vertical cross section showing the piston with the imperforate washers lifted.

Referring to the drawing, my improved hand pump comprises a tubular cylinder 1, having an end 2 welded, as at 4, against an inturned end 30 flange 3. Adjacent the other end of cylinder 1 is provided an outlet port 5.

A closure member 6 is provided for the other end of cylinder 1, having an external flange 7 and a centrally located cup-like flange 8 extended 35 into a tubular guide flange 9 adapted to receive and guide the piston rod assembly. The cap 6 is secured to cylinder 1, as by screws 11. A cap plate 12 is provided to seat on top of closure member 6 and be secured thereto, as by screws 13, thus providing a closure for packing 10 secured in the cup-part 8.

A piston rod herein illustrated as a tubular member 17 is provided, having on its upper and outer end a handle 18 associated with a hub 19 45 which is provided with a socket 20 in which the tubular piston rod 17 seats and is secured, as by pin 21. The lower end of hub 19 is externally threaded, as at 22, to receive an interiorly threaded cup-like member 23 having an inwardly directed flange 24 adapted to engage the upper end 50 of a slidably tubular member 14 which extends over piston rod 17.

To the other end of piston rod 17 is secured a stud member 25 which extends into piston rod 55 17 and is secured thereto, as by pin 26. On stud

25 are secured washers 28, 29, 30 and 32 by means of screw 31. Of these washers 28, 30 and 32 are rigid and 29 is flexible and cupped. All the washers, 28, 29 and 30, are provided with aligned passages 33. Slidably on piston rod 17 above washer 28 are the imperforate washers 16 and 27, of which 16 is rigid and 27 a soft or rubber washer. The slidable tubular member 14 is adapted to engage the rigid washer 16 and to be forced against same by means of threaded cup 23 when the latter is screwed on hub 19.

In the end plate 2 are provided two valve passages, in one of which is positioned valve 34, which is provided with an outwardly directed flange 35 adapted to be welded or brazed to the 15 outer face of end plate 2. This valve part 34 is exteriorly threaded, as at 36, to provide a coupling nipple while its inner edge is beveled, as at 37, to provide a valve seat against which the valve plate 38 is adapted to be pressed by the 20 flat spring 40 secured thereon, as by button 39. The spring 40 is provided with a U-shaped bend 41 adapted to be secured by pin 42 extending between wings 43 integral with valve member 50. The tension of spring 40 is reinforced by a wire 25 spring 45.

The valve member 50 is provided with an exteriorly threaded stud adapted to mate with the interiorly threaded socket of valve part 44, each of these members being provided with complementary valve chambers so that when screwed together, they mutually lock each other on end plate 2 and secure a screen partition 52 in the valve chamber, above which is positioned the ball valve 60. The valve part 44 is further provided with an exteriorly threaded nipple 46 for which is provided a threaded cap 47 which is secured to the valve, as by chain 48 and screw 49.

In operation, it will be apparent that my improved pump can be utilized in various exigencies, either as a pressure pump, in which case the tubular slide 14 is screwed down upon piston rod 17 to force imperforate washers 16 and 27 into close engagement with the perforate washers 28, 29, and 30 to provide an imperforate piston. Air will then be admitted to the lower end of the cylinder through valve 34 on the upstroke of the piston, and forced out through valve 44 on the downstroke of the piston.

Alternately when desired, imperforate washers 50 16 and 27 may be freed by screwing up cap 23 on hub 19, thus permitting imperforate washers 16 and 27 to separate from perforate washers 28, 29, and 30, as is illustrated in Figure 4, and by placing cap 47 on valve 44 the device can be used 55

as an ordinary liquid lift pump, the water or other fluid entering through valve 34 on the upstroke, and passing through orifices 33 on the downward stroke and then being lifted on the 5 next upstroke and discharged through port 5.

Various modifications will readily suggest themselves to those skilled in the art, but within the scope of the present invention, as claimed.

Having fully described my invention, what I 10 claim is:

1. In a pump having a cylinder and a piston rod, a perforate piston secured on the rod, an imperforate washer slidably mounted on the rod above the perforate piston, a tubular member 15 slidable on the rod adapted to engage the imperforate washer, said tubular member extending with the rod outside of the cylinder and means for forcibly sliding the tubular member on the

rod to force the imperforate washer into sealing engagement with the perforate piston.

2. In a pump having a cylinder and a piston rod, a cup washer interposed between rigid disk washers secured to the end of the rod, all of said washers provided with aligned perforations, a compression washer slidable on the rod above 5 said fixed perforate washer and adapted to cover said perforations, a rigid follower washer slidable on the rod above the compression washer, a 10 tubular member slidable on the rod and adapted to engage the rigid follower washer, said tubular member extending with the rod outside of the cylinder, and threaded nut means on the rod outside of the cylinder engaging the outer end of 15 the tubular member.

SEYMOUR J. BAUM.
